UNITED STATES PATENT OFFICE.

BETTIE H. FRANK, OF NEW YORK, N. Y.

GARMENT-SUPPORTER.

SPECIFICATION forming part of Letters Patent No. 661,046, dated November 6, 1900.

Application filed March 7, 1900. Serial No. 7,678. (No model.)

To all whom it may concern:

Be it known that I, BETTIE HARRIS FRANK, a citizen of the United States, residing in the city of New York, borough of Manhattan, in 5 the county and State of New York, have invented a certain new and useful Improvement in Garment-Supporters, of which the following is a specification.

The invention relates more particularly to 10 skirt-supporters, and belongs to that class in which hooks attached to the band of the waist receive corresponding eyes on the skirt-band.

The invention consists of a flat strip of 15 sheet metal or other suitable material having prongs or sharp-pointed projections at proper intervals upon its edges, adapted to be engaged in the fabric and bent over to insure a reliable hold and having vertical hooks, 20 formed by cutting the strip nearly across at the required places and forcing outward the material or tongue lying between two adjacent cuts to a position in a plane parallel with the body of the strip, but slightly offset there- 25 from, and in sheet-metal eyes also provided with attaching-prongs and having each a rectangular slot or opening adapted to engage its hook on the strip. The hooks lie but little out of the plane of the strip, just suffi- 30 ciently to allow the eyes to engage easily, and by reason of the flatness of all the parts the supporter causes no discomfort to the wearer and when covered by a belt produces no apparent change in the surface of the latter and 35 is entirely concealed thereby. The connecting metal between the tongue and body of the strip is offset as nearly as may be at a right angle thereto and serves to prevent accidental disengagement by offering a stop to the 40 interior lower edge of the slot, and in the most complete form of the invention the upper edges of the strip are bent rearwardly to form narrow flanges adjacent to the hooks and serve as additional safeguards against 45 displacement of the eyes when in position.

The accompanying drawings form a part of this specification and show what I consider the best means of carrying out the invention.

Figure 1 is a rear view showing the location 50 and general arrangement of the supporter upon a waist and skirt. The remaining fig-

ures are on a larger scale. Fig. 2 is a face view of the strip after forming and before the prongs have been bent to position to engage the garment. Fig. 3 is a corresponding view 55 of one of the eyes. Fig. 4 is a face view corresponding to Fig. 2, but with the eyes in place and showing at the right-hand end the prongs of both members bent to the position to engage the garments. Fig. 5 is a section 60 taken on the line 5 5 in Fig. 4.

Similar letters of reference indicate the same parts in all the figures.

A is a waist, B the skirt, and C the skirt-band at the line of junction between them. 65

D is a strip of sheet metal, thin steel, brass, or other suitable material shaped by dies or otherwise with sharp-pointed projections or prongs D' D' at the ends, the prongs D² D² on the upper edge, and corresponding prongs 70 D³ D³ on the lower edge, all in the same plane with the body of the strip, but adapted to be bent at right angles thereto, as shown in Fig. 5, to pass through the band of a shirt-waist and engage the latter reliably by folding 75 down on the inner face thereof, as will be understood. Near each end is a pair of cuts or narrow slits extending from the upper edge of the strip nearly across, forming a tongue D⁴ between them, which is forced outwardly by 80 the dies either at the cutting or at a subsequent operation and shaped to lie parallel with the face of the strip, but separated therefrom about the thickness of the metal.

The eyes E E are formed by dies from the 85 same or other suitable material. They are of general rectangular shape, carrying a prong E' at each end near the bottom and the prongs E² E² on the lower edge near each lower corner, by which the eyes are secured to the inner 90 face of a skirt-band at sufficient distance apart to match to the tongues or hooks D⁴ on the strip, with the upper portion free to allow easy engagement with the latter. Each has a rectangular slot or opening e, having a 95 width and height sufficient to admit the hook and pass downward thereon until the eye lies flat upon the strip, with its lower portion below the junction of the hook with the body and about coincident with the lower edge of 100 the latter.

The offset of the hook at d⁴ is on a straight

line and as nearly as practicable a right angle, so that when the strip and eyes are compressed by the ordinary belt (not shown) any tendency toward disengagement by an upward movement is resisted by the offset, and as a further barrier I prefer in some cases to bend a portion of the metal between the cuts d d and the adjacent prong D^2 rearwardly to form the slight flanges D^5 D^5 , against which the upper edge of the eye will strike and further movement be arrested before disengagement takes place. The efficiency of flanges D^5 is increased by reason of the angular position assumed by the eye in riding upward on the hook, thus forcing the upper edge directly against them.

The supporter may be easily attached to the garments in the desired position without sewing, and several waists and skirts thus equipped may be worn interchangeably without requiring readjustment of the supporters.

Besides the important advantage offered by the extreme thinness and avoidance of protruding portions the supporter may be of comparatively little width and will therefore serve successfully with narrow belts.

If the strip be properly located upon the waist, and the eyes, with their closely-fitting slots, correspondingly placed upon the skirt-band, the garments when joined will always assume the proper relative positions and maintain them without further attention or fastening.

The smooth curve described by the thin pliant metal increases the beauty of the waist-line and adds to the comfort of the wearer.

The sizes and proportions of the parts may be varied within wide limits to suit varying conditions or changes in fashions, and both members may be ornamented by enameling or plating, as usual.

The flanges D^5 may be dispensed with, de-

pending upon the offsets d^4 alone to prevent disengagement.

45

I claim—

1. In a garment-supporter, a strip D of thin sheet metal, attaching-prongs thereon and rectangular hooks D^4 D^4 near the ends of said strip and formed integral therewith, in combination with eyes E E having attaching-prongs at the lower portions thereof, and having the rectangular openings e e , matching to said hooks, said eyes adapted when engaged to lie within the margins of said strip and with the offsets d^4 d^4 joining said hooks to said strip on a straight line and serving with said openings as stops to prevent the disengagement of said hooks and eyes, all arranged to serve substantially as and for the purposes herein specified.

2. In a garment-supporter, a strip D of thin sheet metal, attaching-prongs thereon and rectangular hooks D^4 D^4 at the ends of said strip and formed integral therewith, and the offsets d^4 d^4 on a straight line and at right-angles thereto, in combination with eyes E E having attaching-prongs at the lower portions thereof and having the rectangular openings e e matching to said hooks, the said eyes adapted when engaged to lie within the margins of said strip the said offsets serving as stops to prevent the disengagement of said hooks and eyes, and the flanges D^5 D^5 on the upper edge of said strip adjacent to said hooks serving as additional stops for preventing disengagement, all substantially as herein specified.

In testimony that I claim the invention above set forth I affix my signature in presence of two witnesses.

B. H. FRANK.
